ERD V. CROWELL, OF LOS ANGELES, CALIFORNIA

CEMENT RETAINER

Application filed March 17, 1930. Serial No. 430,434.

This invention is an improvement in that type of cement retainer which is adapted to be lowered and anchored in well casing with a valvular control for the bore of the retainer permitting flow of cement or circulating fluid into the surrounding well bore but preventing return flow past the retainer.

It is an object of the invention to positively lock the retainer against axial displacement in either of opposite directions in the well casing, and to tightly seal the retainer by utilizing the pressure of the flow.

It is a further object of the invention to arrange the valvular control so that it will prevent return flow of the discharged material past the retainer but will permit the discharged material exerting pressure against the sealing medium for tightly packing off the retainer.

It is a still further object of the invention to provide an engagement between the retainer and a string of tubing whereby the retainer may be conveniently run into the well casing, with said engagement forming a fluid tight connection which is readily releasable in order that the tubing may be elevated with relation to the anchored retainer.

It is a still further object of the invention to guide the string of tubing with relation to the retainer in order that their fluid tight connection may be readily made, and to provide means whereby the retainer may be slowly run into the well casing without sudden dropping.

Further objects of the invention will be readily understood from the following description of the accompanying drawing, in which:

Fig. 1 is a front elevation, partly in axial section, showing the retainer being run into a string of well casing.

Fig. 2 is a similar view showing the retainer anchored in the casing string.

Figs. 3 and 4 are transverse sections on the lines 3-3 and 4-4 respectively of Fig. 2.

The cement retainer is adapted to be run into well casing A by lowering a string of tubing B, and is adapted for positive anchoring against displacement in either of oppo-

site directions at a casing shoe 1 which is suspended from the casing string, by means of expansible slips 2 mounted on the retainer and adapted to engage a cooperating annular recess 3 in the bore of the casing shoe.

As an instance of this arrangement the recess 3 forms abutment shoulders 4 at its respective axial ends, with said shoulders at right-angles to the axis of the casing, and the body 6 of the retainer is annularly grooved at 7 for reception of the expansible slips 2, so that the slips may contract in groove 7 for lowering the retainer into the well casing as shown in Fig. 1, and will automatically expand when aligned with recess 3 so as to positively lock the retainer against longitudinal displacement in either of opposite directions in the casing by the seating of the expanded slips between the right-angular abutment shoulders 4 as shown in Fig. 2.

The slips 2 are preferably arcuate structures recessed at their inner surfaces so as to form axially spaced sockets 8 which are adapted to partially house expansion springs 9, and the inner ends of the springs bear against the base of groove 7 so as to tend to outwardly shift the slips for seating engagement between shoulders 4. The movement of the slips may be limited by bolts 10 which slidably fit in pockets 11 formed in the outer surfaces of the slips, with the inner ends of the bolts extending through suitable openings at the inner ends of the pockets and threaded into the body 6.

When anchored in the casing shoe, the retainer is packed-off relative to the casing string A, and for this purpose a packing sleeve 12, preferably of rubber, is mounted on the body 6 with its ends engaged by cooperating abutments 13-14 which are preferably undercut as shown at 15 in order to prevent radial displacement of the packing. The abutment 13 may be formed on body 6 above the groove 7, and in order to provide for convenient assembly the abutment 14 is preferably formed on a head 5 which is adapted for detachable connection to the body 6 by means of a threaded engagement 16.

The retainer has an axial bore for flow of

cement, circulating fluid, etc.; and a valvular control which is mounted in the bore is adapted to open for downward flow through the retainer and thence through the open 5 lower end of the casing into the surrounding well bore, but is adapted to close against return flow past the retainer while permitting the discharged material to exert pressure against packing sleeve 12 for expanding 10 it to fluid tight engagement with the bore of the casing.

For this purpose the valvular control is adjacent the upper end of the retainer and preferably comprises a valve seat 17 formed 15 in the bore of head 5, with a downwardly opening valve 18 engaging the seat and normally yieldably retracted to closed position by a spring 19; and below the valvular control the bore of body 6 is ported as shown 20 at 20, with the ports communicating with an annular recess 21 in the inner periphery of packing sleeve 12 so that the pressure of the flow which is discharged past open valve 18 and through the bore of the retainer is exerted 25 against the packing for expanding it to operative position, and when the valve closes against return flow past the retainer the pressure of the discharged material is still exerted against the packing sleeve through the 30 ports 20 in order to maintain a fluid tight seal.

The tubing string B releasably engages the retainer so that it may lower the retainer to operative position and may then be readily disengaged for elevation relative to the anchored retainer. As an instance of this 35 arrangement the upper end of the head 5 of the retainer preferably forms a valve seat 22 axially spaced above valve 18, and a co-operating valve head 23 which is adapted to form a ground joint with valve seat 22 is suspended from the tubing string B. By the abutment of head 23 against the seat 22 the tubing string B may thus force the retainer 40 downwardly through the casing string A until the retainer anchors in casing shoe 1, with the ground joint 22-23 maintaining a fluid tight engagement, which however is readily releasable for elevating the tubing 45 string with relation to the anchored retainer.

In order to prevent sudden dropping of the retainer as it is forced downwardly through the casing, frictional retarding 55 means shown as bowed springs 24 are preferably mounted on head 5 so as to yieldably engage the wall of the bore of the casing; and in order to guide the tubing B into axial alinement with the retainer so as to insure 60 a tight engagement at ground joint 22-23, similar bowed springs 25 are preferably mounted on the tubing adjacent the head 23 so that the yieldable frictional engagement of springs 25 with the wall of the bore of the 65 casing will accurately center the tubing

string. The springs 24 and 25 are preferably fixed at one end as shown at 26, and at their opposite ends are adapted for limited axial movement by pin and slot connections 27 in order that the springs may readily 70 yield and expand.

In operation the retainer is forced downwardly through the casing string as shown in Fig. 1 and is then automatically and positively locked in casing shoe 1 by the engagement of the expanded slips 2 with the shoulders 4 as shown in Fig. 2. The weight of the string of tubing then maintains a leak-proof engagement at the ground joint 22-23 so that all of the circulating fluid, cement, etc., which is discharged downwardly through the tubing flows past the open valve 18 and through the bore of the retainer for discharge into the surrounding well bore; and the pressure of the flow is exerted 80 through ports 20 against the packing 12 for expanding it to operative position so as to tightly seal the retainer against leakage upwardly past the same into the casing string. 85

When the cementing operation is completed 90 the valve 18 closes against return flow, with the pressure of the discharged material still directed through ports 20 for maintaining the packing sleeve 12 in operative position; and the tubing string may then be readily disengaged from the anchored retainer at the ground joint 22-23 in order that the tubing may be conveniently withdrawn. In the event of leakage past the packing sleeve during the cementing operation, the ground joint 22-23 also provides for temporary elevation 100 of the tubing string with relation to the anchored retainer in order that circulating fluid may be discharged from the tubing into the casing string for flushing out any accumulated cement. 105

When it is subsequently desired to open the bore of the cemented casing, the anchored retainer is drilled through in usual manner, and for this purpose is made of usual relatively frangible material such as cast iron which offers no appreciably obstruction to a usual drill.

The invention thus provides a cement retainer which may be positively locked in place 115 against longitudinal displacement in either of opposite directions, whereby pressure of the flow in either of opposite directions cannot disturb the anchored retainer, but with the pressure of the flow adapted to operatively expand a packing element of the retainer so as to form a fluid tight seal, and the anchored retainer readily releasable from the tubing string by which it is lowered to operative position, in order that the tubing may be conveniently elevated and withdrawn. 120

I claim:

1. In combination, a casing string having an interior annular recess forming axially spaced abutment shoulders at right-angles to 130

- the axis of the casing, a plug adapted to be lowered in the casing string, expansible slips mounted on the plug and adapted for automatic expansion upon alinement with the angular recess so as to seat between the right-
angular abutment shoulders for anchoring the plug against longitudinal displacement in either of opposite directions, the plug having a bore, and a downwardly opening normally closed valve for said bore. 5
2. In combination, a casing string, a plug adapted to be lowered in the casing string, means for anchoring the plug in the casing string, packing on the plug adapted to engage the wall of the casing string, the plug having a bore with ports opening therefrom in back of the packing, and a downwardly opening normally closed valve for said bore, the valve being positioned above said ports. 15
3. In combination, a casing string, a plug adapted to be lowered in the casing string, means for anchoring the plug in the casing string, the plug having a bore, a downwardly opening normally closed valve for said bore, and a tubing string adapted for non-rotary readily disengageable fluid tight abutment against the upper end of the plug for lowering it in the casing string. 20
4. In combination, a casing string, a plug adapted to be lowered in the casing string, means for anchoring the plug in the casing string, the plug having a bore, a downwardly opening normally closed valve for said bore, and a tubing string having a head adapted for readily disengageable ground joint abutment against the upper end of the plug for lowering it in the casing string. 25
5. In combination, a casing string, a plug adapted to be lowered in the casing string, means for anchoring the plug in the casing string, packing on the plug adapted to engage the wall of the casing string, the plug having a bore with ports opening therefrom in back of the packing, a downwardly opening normally closed valve for said bore, the valve being positioned above said ports, and a tubing string adapted for readily disengageable fluid tight abutment against the upper end of the plug for lowering it in the casing string. 30
6. In combination, a casing string, a plug adapted to be lowered in the casing string, means for anchoring the plug in the casing string, the plug having a bore, a downwardly opening normally closed valve for said bore, means for frictionally retarding lowering of the plug in the casing string, a tubing string adapted for non-rotary readily disengageable fluid tight abutment against the upper end of the plug for lowering it in the casing string. 35
7. In combination, a casing string, a plug adapted to be lowered in the casing string, means for anchoring the plug in the casing string, the plug having a bore, a downward-
ly opening normally closed valve for said bore, a tubing string adapted for non-rotary readily disengageable fluid tight abutment against the upper end of the plug for lowering it in the casing string, and means on the tubing string engaging the wall of the casing string for alining the tubing string with the plug. 40
8. A cement retainer comprising a plug having a bore, packing on the plug, ports opening from the bore of the plug in back of the packing, and a normally closed downwardly opening valve for the bore above said ports. 70
9. A cement retainer comprising a plug adapted to be lowered in well casing, the plug having a bore, a normally closed downwardly opening valve for said bore, the upper end of said bore forming a seat, and a head adapted for suspension from a tubing string for readily releasable ground joint abutment against said seat. 75
10. A cement retainer comprising a plug adapted to be lowered in well casing, the plug having a bore, packing on the plug, ports opening from the bore of the plug in back of the packing, a normally closed downwardly opening valve for the bore above said ports, the upper end of said bore forming a seat, and a head adapted for suspension from a tubing string for readily releasable fluid tight abutment against said seat. 80
11. A cement retainer comprising a plug adapted to be lowered in well casing, the plug having a bore, a normally closed downwardly opening valve for said bore, the upper end of said bore forming a seat, a head adapted for suspension from a tubing string for non-rotary readily releasable fluid tight abutment against said seat, and means on the plug for frictionally retarding its lowering into the well casing. 85
12. A cement retainer comprising a plug adapted to be lowered in well casing, the plug having a bore, a normally closed downwardly opening valve for said bore, the upper end of said bore forming a seat, a head adapted for suspension from a tubing string for non-rotary readily releasable fluid tight abutment against said seat, and means on the head for guiding it into alinement with the seat. 90
13. A cement retainer comprising a plug adapted to be lowered in well casing, the plug having a bore, a normally closed downwardly opening valve for said bore, the upper end of said bore forming a seat, and a head adapted for suspension from a tubing string for non-rotary readily releasable fluid tight abutment against the seat. 95
- In testimony whereof I have affixed my signature.
